UNITED STATES PATENT OFFICE.

JAMES McCORMACK AND EDWARD E. LOUISELLE, OF SOUTH FRAMINGHAM,
MASSACHUSETTS.

COLLAPSIBLE BOX.

1,262,612.

Specification of Letters Patent.

Patented Apr. 9, 1918.

Application filed October 16, 1916. Serial No. 125,771.

To all whom it may concern:

Be it known that we, JAMES McCORMACK and EDWARD E. LOUISELLE, each a citizen of the United States, and each a resident of 5 South Framingham, in the county of Middlesex, in the State of Massachusetts, have jointly invented a certain new and useful Improvement in Collapsible Boxes, of which the following is a specification, reference being had to the accompanying drawings.

This invention relates to collapsible boxes or cases of the type used more or less commonly for marketing, or transporting, produce such as garden truck, and farm products generally; our immediate purpose being to provide a strong, serviceable, and reasonably cheap, box in which such produce may be sent to market, by team or train; our said case being so constructed that it may be 20 quickly collapsed and packed into small space for more conveniently returning it to the initial shipping point. In the annexed drawings Figure 1 is a perspective view of a case embodying our present invention and 25 Fig. 2 shows the said case collapsed.

Fig. 3 is a top view of the meeting corners of two of the collapsible sides of the said case and of an automatic corner latch which forms an important feature of novelty in 30 connection with our improvement. Fig. 4 is a relatively enlarged perspective view of the latch members in the positions which they assume when two sides of the case are approaching each other and are just about to 35 interlock with each other.

Fig. 5 is a perspective view of the member 15 and Fig. 6 is a similar view of the spring controlled member 20.

In these drawings the numeral 10 indicates the bottom of the case, 11 and 12, 40 denote two opposing sides that are hinged to said base and are adapted to be folded down upon the base, as seen in Fig. 2 of the drawings.

The other two sides, 13 and 14, are also 45 hinged to the base 10 and are adapted to be folded down upon the sides 11 and 12, thus collapsing the case into small space for packing or transportation. At each corner 50 of the set-up case we have provided a latch which operates automatically, as the sides are swung open, to latch together the meeting corners, said latch being indicated as a whole, in Figs. 1 and 3, by the letter *a*. The 55 said latch includes a plate 15, which is se-

cured to one box side by screws inserted at 16, a plate 17 which is secured to the companion box side by screws inserted at 18-19, and a spring-controlled slide 20 which is located in the angle formed by the plate 15 60 and is held in position by a lip 21 (see Fig. 4), said plate 15 having an inset portion 15^b to allow of positioning thereof interiorly of the plate 17.

The box side to which the plate 15 is 65 screwed is notched, or otherwise cut away to receive the slide 20 and to form an abutment for the lower end of the spring 22 by means of which the said slide is forced upward. The upper face of the slide is 70 provided with an opening 23 which is suitably positioned to slip over the lower end of a stud 24, which extends downward from the top plate of the member 17, when the latch parts are in their closed or locking 75 positions, as seen in Fig. 3.

In the operation of opening up the sides of the case, the side which carries the plate 17 is opened first.

The side which carries the members 15 80 and 20 is then opened and, when it has nearly reached its vertical position, the said plates 15 and 20 pass under the top plate of the member 17 and when the lower end of the stud 24 engages the rounded, or 85 beveled, edge 20^a of the slide, it forces the slide down and holds it down until the opening 23 moves into register with the stud, when the spring 22 forces the slide upward, over the stud, thus locking the 90 corner members 15 and 17 together. At the same time an inwardly projecting lip 17^a on the member 17 enters an opening 15^a in the inset portion 15^b of the plate 15 and then serves as a lock to prevent the 95 latched box sides from springing apart when the case is filled with goods.

When, however, it is desired to collapse the box sides it is only necessary to move the slide 20 downward by pressing down 100 upon a lip 20^b formed at the lower edge of the member 20. The slide is thereby released from stud 24, and the box side which carries members 15 and 20 may be first folded down, leaving the companion side 105 free to follow.

Our described latching device is strong, and inexpensive to manufacture, being mainly punched from sheet metal, and it may be very quickly manipulated either to 110

open and latch the sides or to unlatch and collapse said sides.

Having thus described our invention, we claim as new and wish to secure by Letters 5 Patent:—

1. A collapsible case, with foldable sides and a latch for engaging each corner of the case, including a perforated angular plate, one wing of said plate having a lip 10 at an angle thereto, a second angular plate with one wing thereof provided with a lip at an angle thereto, received by the perforation of the first-referred to plate, a resiliently controlled member received within 15 the angle of the latter plate and having a slidable connection with said second angular plate, and held in position in connection with said first-referred to plate by the lip of the latter.
- 20 2. A collapsible case, with foldable sides and a latch for engaging each corner of the case, including a perforated angular plate, one wing of said plate having a lip at an angle thereto, a second angular plate with 25 one wing thereof provided with a lip at an angle thereto, received by the perforation of the first-referred-to plate, a resiliently controlled member adapted to fit into the angle of the first-referred-to angular plate, with the lip of the latter engag-

ing, and aiding to retain said resiliently controlled member in position, said second referred to angular plate having a stud depending from its underside and received by an aperture in said resiliently controlled member. 35

3. A collapsible case having foldable sides, a latch for engaging each corner thereof, including a perforated angular plate, one wing of said plate having a lip at an angle 40 thereto, the other wing of said plate itself being angular, for a portion of its length, with a case-side, a resiliently controlled member received within the angle of said angular plate, and engaged by said lip of 45 the latter, and a second angular plate, with its upper portion overlying said first-referred-to plate and said resiliently-controlled member, said second referred to angular plate having one wing thereof provided with a lip entering the perforation of the first-referred to angular plate, said second referred to angular plate having a depending stud entering an opening in said resiliently controlled member, said latter 55 member having a lip adapted to be finger-actuated in releasing or overcoming the action of its resiliency.

JAMES McCORMACK.
EDWARD E. LOUISELLE.
